UNITED STATES PATENT OFFICE.

MASON BRADFIELD, OF LOS ANGELES, CALIFORNIA, ASSIGNOR TO EMMA N. BRADFIELD, OF LOS ANGELES, CALIFORNIA.

CONVEYER.

SPECIFICATION forming part of Letters Patent No. 709,737, dated September 23, 1902.

Application filed May 24, 1901. Serial No. 61,758. (No model.)

To all whom it may concern:

Be it known that I, MASON BRADFIELD, a citizen of the United States, residing at Los Angeles, in the county of Los Angeles and 5 State of California, have invented a new and useful Conveyer, of which the following is a specification.

This invention relates to conveyers, and particularly to devices adapted to convey 10 small quantities of material a comparatively short distance by a series of trips or movements; and some of the objects of the invention are to provide a device of this character which will be simple, strong, and cheap in 15 construction and at the same time positive and effective in operation.

It is also an object of this invention to provide a device of this character constructed to automatically discharge the contents thereof 20 upon the slackening of the suspending or supporting means until the conveyer rests on its bottom and the tightening or elevation of the supporting means.

A further object of the invention is to provide 25 a device with an auxiliary or supplemental bail so connected therewith as to effect the dumping or overturning of the device when disengaged from the bail proper.

Another object of the invention is to provide 30 a hook so constructed that when released from engagement with the bail proper it will turn or rotate about the point of connection of the eye thereof with the supporting means.

With these and other objects in view the 35 invention consists, essentially, in the construction, combination, and arrangement of parts substantially as hereinafter more fully described in the following specification and illustrated in the accompanying drawings, 40 forming part of this application, in which—

Figure 1 is a side elevational view of a conveyer-bucket provided with my improvements. Fig. 2 is a view similar to Fig. 1, showing the bucket in the dumping or discharging position. Fig. 3 is a sectional view 45 showing the interior construction of the bucket, the bails being broken away. Fig. 4 is a view similar to Fig. 2, illustrating a modified form or manner of attaching the 50 bails to the bucket. Fig. 5 is a detail view,

on an enlarged scale, of a form of hook and attaching devices employed; and Fig. 6 is a longitudinal central section through the hook and attaching devices.

Similar characters of reference designate 55 corresponding parts throughout the several views.

It will be understood that this invention is not limited to use upon or in connection with conveyer-buckets of the construction herein 60 shown and described, as the same is only typical, illustrating one use or application of the invention, for it is obvious that the invention may be applied in numerous ways.

The drawings illustrate the invention applied to a conveyer-bucket designed to convey or transport solid or semiliquid matter along a predetermined line of travel, such as removing earth, stones, gravel, mud, and similar materials from excavations or conveying 70 coal to and from the holds of vessels and for similar purposes, as will be readily understood.

The reference character 1 designates a bucket, of any preferred form or construction, 75 preferably provided with an extension-rim or annular flange 2 to protect the bottom of the bucket when in operation.

Formed on or connected with the bucket 1, preferably by rivets or other devices 3, is a 80 bail or handle 4, desirably constructed with an intermediate offset or loop 5, and the bail may be connected with the bucket, as shown at 6, Fig. 1—that is, by being riveted thereto adjacent to the top and bottom of the bucket 85 and having the extremities of the bail turned upon themselves to form hooks or eyes 7, Figs. 1 and 2, or the bail 4 may be connected with the bucket adjacent to the free edge thereof only, as shown at 8 in Fig. 4 of the 90 drawings, the latter construction effecting a saving of material and decreasing the weight of the bucket, as will be readily understood.

When the bail 4 is connected with the bucket only at the free upper edge thereof, 95 substantially as shown in Fig. 4, then hooks or ears 9 may be secured near the bottom of the bucket, upon opposite sides thereof, essentially as illustrated in said figure, or other means may be employed to afford connection 100

between the auxiliary or supplemental bail 10 and the bucket 1, if found desirable in practice.

A supplemental or auxiliary bail 10 may be 5 employed formed of one piece of bar metal or other suitable material and is preferably provided with an intermediate eye or loop 11, formed therein or connected therewith and with eyes or rings 12 at the extremities thereof 10 of constructed to engage the hook 7 upon the diametrically opposite sides of the bucket 1 and to move upon said hooks during the operation of the device.

Referring to Figs. 1, 4, 5, and 6, there is 15 illustrated an engaging device embodying a hook 13, preferably provided with an integral eye or ring 14, substantially as illustrated in Figs. 5 and 6, and the hook is desirably constructed with an extension or lug 15, 20 Fig. 6, and the construction of the hook 13 is preferably such that when the conveyer or bucket is hung thereon by its bail-loop 5 the center of gravity of said hook will be out 25 of a straight line connecting the eye of said hook and the bearing-point of the loop 5 on the hook, whereby when the conveyer or bucket rests on its bottom and the supporting means 16 is slackened the hook will swing upon the point of connection of its eye with 30 said means and automatically be disengaged from the loop 5. This operation may be aided by the connection of the bail 10 with said hook as to be slightly off the center of gravity, so that when the hook is released from 35 engagement with the loop 5 of the bail 4 by slackening or the descent of a rope or cable 16 the hook will turn or rotate about the point of connection of the eye thereof with the supporting means or rotate into a reverse position 40 as shown in Fig. 4 of the drawings.

By means of the aforesaid rotation or reversing of the hook 13 when released from engagement with the bail accidental engagement of the former with the latter is rendered 45 impossible when the rope or cable 16 is elevated to effect the dumping of the contents of the bucket through the mediation of the auxiliary bail 10, as shown in Figs. 2 and 4 of the drawings.

50 A clip 17, Figs. 5 and 6 of the drawings, is preferably constructed with a bifurcated end 18, in which is pivoted the extension or lug 15 of the hook 13, and a headed rod 19 is preferably swiveled in the clip 17, substantially as 55 shown in Fig. 6, and the end of the rod may be coiled upon itself, essentially as shown at 20, Figs. 4 and 5, after passing through an eye or ring 21 in a spring clip or snap 22.

A spring clip or snap 22 may be employed 60 having a hook portion 23, with which is operated a spring-actuated pivoted jaw 24 to effect detachable connection with the eye or loop 11 of the supplemental bail, the clip 22 being shown in engagement with said loop in 65 Figs. 1 and 4 and detached therefrom in Figs. 5 and 6 of the drawings.

The operation of the invention will be read-

ily understood from the foregoing description when taken in connection with the accompanying drawings and the following explanation thereof. The hook 13 is caused to engage the loop 5 in the bail 4, the snap 22 having been previously connected with the eye 11 in the supplemental bail, and the bucket is then filled with the material to be 70 conveyed or transported, it being understood that the rope or cable 16 is always kept taut after the hook has been brought into engagement with the bail, and when it is desired to discharge the contents of the bucket it is only 75 necessary to lower or slack up on the rope or cable 16, which effects disengagement between the hook and bail, the conveyer or bucket at the time resting upon its bottom, so that when the rope or cable 16 is raised or 80 tightened up there will be no possibility of the hook reengaging with the bail, by reason of the hook then being directed away from the latter. By the continued elevation or 85 tightening up of the rope or cable the supplemental bail, being pivotally connected with the bucket near the bottom thereof, will effect the overturning of the same, thereby 90 discharging the contents of the bucket, the parts then being in the position substantially 95 as illustrated in Fig. 4 of the drawings.

It is not desired to confine this invention to the specific construction, combination, and arrangement of parts herein shown and described, and the right is reserved to make all 100 such changes in and modifications of the same as may come within the spirit and scope of the invention and that may be found necessary in practice.

What I claim is—

1. A conveyer provided with a main bail and having a supplemental bail pivotally connected therewith, a hoisting-line and a device attached thereto and connected with the latter bail constructed to support the conveyer 110 in carrying position when in engagement with the former bail and when disengaged therefrom to rotate about the point of connection thereof with said line out of reengagement therewith to effect the discharge of the conveyer upon the tightening of said line.

2. A conveyer provided with a main and a supplemental bail, a hook connected with the latter constructed to detachably engage the former when forced away from the conveyer 120 and to rotate about the point of suspension thereof out of accidental reengagement with the main bail when such force is released.

3. A conveyer provided with a main and supplemental bail, a supporting-line and a 125 hook attached thereto and detachably connected with said supplemental bail constructed to retain engagement with said main bail while said line is taut and to rotate about the point of connection thereof with said line 130 out of such engagement when said line is relaxed to prevent accidental reengagement.

4. A conveyer provided with a main and a supplemental bail, a supporting-line and a

130

hook attached thereto and having swivel connections with said supplemental bail constructed to engage said main bail when said line is taut and to rotate upon said swivel 5 and the point of connection thereof with said line out of engagement when said line is relaxed.

5. A conveyer having a main bail rigidly secured thereto and having a supplemental 10 bail movably connected therewith near the bottom thereof, a supporting line, a snap connected with said supplemental bail and a hook swiveled to said snap at one side and connected at the straight end with said line, 15 whereby the hook retains engagement with said main bail while the line is taut and rotates on said swivel and the point of connection

thereof with said line out of reengagement therewith when said line is relaxed.

6. An engaging hook having a loop or eye 20 at one end thereof to receive a hoisting-line and provided with an apertured lug or ear near the opposite end to be connected with the article employed, said hook being constructed to rotate about the point of connection thereof with said line when the line is relaxed.

In testimony whereof I have signed my name to this specification in the presence of two subscribing witnesses.

MASON BRADFIELD.
